Pierre Lamoie
ATTORNEY

UNITED STATES PATENT OFFICE.

CARL O. LARSON, OF SEATTLE, WASHINGTON.

AUTOMOBILE DIRECTION SIGNAL.

Application filed May 10, 1927. Serial No. 190,206.

This invention relates to vehicle direction and stop signals of the semaphore type, and more especially to improvement to the signal device which was shown and described in 5 patent application, Serial No. 68,558, filed by me November 12, 1925.

The object of my improvements is the perfecting of the semaphore operating mechanism and the provision of a single actuating 10 lever which will render the operation of the signal more efficient, simple and convenient to employ without liability of error.

More specific objects and advantages of the invention will appear in the following 15 description.

The invention consists in the novel construction adaptation and combination of parts hereinafter described and claimed.

In the accompanying drawing,—

Figure 1 is a view partly in elevation and partly in vertical transverse section of devices embodying the invention shown applied; Fig. 2 is a front elevational view of the semaphore controlling mechanisms showing the 25 manner of mounting and arranging the same, the movable parts being represented as occupying the positions which they assume when the semaphores are in the positions in which they are represented in Fig. 1; and 30 Figs. 3 and 4 are detail sectional views on lines 3—3 and 4—4 of Fig. 1.

In carrying out the present invention there is provided a casing 5 which is secured, as by 35 means of bolts or screws 6, to the side wall 7 of an automobile body structure. Said casing is arranged to project at right angles, or nearly so, with respect to the car body, and is open at its outer side as indicated by the numeral 8 in Fig. 1. In the upper portion of 40 the casing is provided a pivot 9 upon which are mounted to be swung outwardly from the casing three semaphores, or signs, 10, 10¹, and 10², which bear, respectively, the legends "Right", "Stop" and "Left". Normally said 45 signs are in substantially vertical positions within the casing as represented by the sign 10 in Fig. 1. The signs are adapted to be selectively swung outwardly with respect to the casing by means of the following described 50 controlling and actuating devices.

To which end, at one side of the pivot 9, each of the signs is connected by means of a pin 11 with an end of a link 12 whose other end is connected by a pin 13 with an arm of 55 a bell-crank lever 14. These levers, one for

each of the signs, are fulcrumed to a pivot 15 extending through plates, as 16, which serve to keep the signs apart.

The other arms of the respective bell-crank levers are connected by means of attachments, 60 such as 17, with ends of wires 18, 19, and 20 passing through guiding tubes 18¹, 19¹ and 20¹, which extend through a pipe 21, to a box 22.

The box 22 is rigidly secured, as by means 65 of screws 23 Fig. 2, to the body structure of the car or, as shown in Fig. 1, to a bracket piece 24 which is rigid with such structure. The box 22 is located interiorly of the car body and in convenient reach of the driver. 70

Within said box, the wire 20 is secured to a slider 25 which is movable in a horizontal guide-way 26 provided in the back wall 30 of the box. The other wires 18 and 19, as shown in Fig. 2, are connected to arms 27 and 75 28 of bell-crank levers which are respectively fulcrumed to pivots 29 located above and below the guideway 26. The complementary arms 27¹ and 28¹ of the respective levers extend across a vertical guideway 31 provided 80 in said wall and are each provided in its free end with a slot 32.

Movable vertically in the guideway 31 is a block 33 having near each of its ends studs 27² and 28², respectively, which are engageable 85 in the slots 32 of the respective bell-crank levers for the purpose of transmitting sign-operating movements to the latter.

The block 33 is also provided centrally of its length with two spaced apart lug elements 90 34 to accommodate therebetween a block shifting finger 35 which constitutes an arm of an actuating lever which extends through the front wall 36 of the box. Said actuating lever is fulcrumed by means of a universal-joint 95 connection comprising a globular element 35² of the lever seating in a corresponding cavity 38 provided in said front wall 36. The outside arm 35¹ constitutes the handle element of the actuating lever. The slider 25 is provided 100 with two spaced apart protuberances 39 and 40, the latter being hollow to accommodate a ball 41 and a spring 41¹ (Fig. 3) which is engageable in spaced apart recesses 42 and 42¹ of the box wall 30 for releasably holding the 105 slider at either end of its travel.

Spring pressed balls, similar to that described above with respect to the slider, are advantageously provided in hollow protuberances 40¹ provided upon the bell-crank 110

lever arms 27 and 28, the respective balls being adapted to take in recesses as 43 and 44 for releasably retaining the ball-cranks in their operating and idle positions. Stops, 5 as 45, are provided for limiting the throw of the levers 27-27¹ and 28-28¹ when influenced by the force of gravity acting to restore the associated signs into their sheathed positions within the casing 5. 46 represents a 10 bumper provided in the casing to overcome the momentum of the signs as they return into their sheathed positions within the casing.

To facilitate the operation of the actuating lever to effect the display of the various signs 15 selectively, index legends as "Right", "Left" and "Stop" as denoted by the numbers 48, 47 and 46, are provided about the lever upon the box wall 36 as shown in Fig. 1. Normally, all of the signs 10, 10¹ and 10² are 20 sheathed within the casing, whereupon the slider 25 occupies the position in which it is shown in Fig. 2, and the block 33 has been shifted from its Fig. 2 position into its neutral position whereat the block extends 25 across the slider 25 so that the space between the lugs 34 of the block is directly between the lugs 39 and 40 of the slider. With the slider and block thus arranged, the finger 35 is held by the said lugs to hold the actuating 30 lever 35-35¹ perpendicular to the plane of the box wall 36. To operate the signal device for exhibiting the "Stop" sign 10, for instance, the operator has simply to press the handle 35¹ of the actuating lever in a direction 35 toward the index legend "Stop" (46) on the box, or in a downward direction in the illustrated assembly. When the handle arm 35¹ of the actuating lever is thus thrust 40 downwardly the complementary arm, or finger, 35 is elevated, carrying therewith the block 33; the stud 27² of which, see Fig. 4, engaging the arm 27¹ of the respective bell-crank lever to force the same upwardly and thereby cause the associated arm 27 to be swung toward 45 the right hand side into the position in which it is represented in Fig. 2. As this occurs a pull is applied through the wire 18, its bell crank connection 14 and link 12 to effect the elevation of the "Stop" sign into the signalling position in which it is shown in Fig. 50 1, and whereat it is held by means of the spring pressed ball (provided in the hollow protuberance 40¹ of lever 27-27¹) engaging in a recess similar to 44, provided in the box wall for the lever above referred to.

For returning a sign from its signalling position into its inoperative position all that is necessary to push the lever handle 35¹ 55 towards its perpendicular relation with the box which results in moving the exposed sign into its unexposed position in the casing and the return of the bell-crank lever into its neutral position as regulated by a stop 45 whereat the same is releasably held by the 60 spring-pressed ball pertaining to the lever

27-27¹ engaging in the corresponding recesses 43. Such movement of this lever also acts to restore the block 33 into its neutral position. The purpose of the slots 32 in the lever arms 27¹ and 28¹, respectively, is to provide bifurcations in such arms whereby the block studs are capable of engagement with the arms 27¹ or 28¹ for moving the same at will in either of two directions; and by having, as shown, one of the branches of each 75 arm bifurcation of shorter length than the companion branch, permitting the studs of the block to be withdrawn from the slot of either arm at neutral without disturbing the same as may be required for operating the 80 various signs. The left hand turning sign 10² is exposed by means similar to those described above with regard to the stop sign. The "Left" sign, however, is operated more 85 directly by means of the actuating lever, the swinging of the handle arm of the latter toward the left hand, as indicated by "Left" index mark 47 (Fig. 1) causing the slider 25 to be shifted by means of the finger 35 toward the right hand, whereupon, a pull is 90 applied through the wire 20, which is attached to the slider, to effect the swinging of the desired sign into its display position. In thus shifting the slider to operate the sign 10², the finger 35 acts against the slider 95 protuberance 40, and in returning the slider to neutral the finger acts against the lug 39.

The invention and the manner of its operation will, it is believed, be understood from the foregoing description.

What I claim, is,—

1. In an automobile signal, the combination of stop and direction signs arranged to swing about a horizontal axis, controlling means connected with the respective signs, an actuating device, and two members movable in planes at right angles to each other and engageable indirectly by said actuating device whereby said controlling means are rendered operable to effect the swinging of either of the signs selectively from its inactive position into its display position.

2. In an automobile signal, the combination of stop and direction signs arranged to swing about a horizontal axis, operating levers connected with the respective signs, controlling levers, flexible connections connecting said controlling levers with said operating levers, an actuating lever, and a member adapted to be carried by said actuating lever into engageable relation with either of the controlling levers whereby the latter may be actuated to effect the swinging of either of said signs selectively into display position and similarly return the signs into their normal inactive positions.

3. In an automobile signal, the combination of movable stop and direction signs, means including members arranged for movements at right angles to each other for oper-

ating the respective signs, and an actuating lever engageable with said members selectively whereby said signs are adapted to be moved at will from their normal unexposed positions into their display positions.

4. In an automobile signal, the combination of stop and direction signals mounted to swing from their normal unexposed positions into display positions, individual operating means provided for the respective signs, a slide included in the operating means for one of said signals, a block adapted for connection with the operating means of another of said signals, and a manually operated device 10 for actuating either of said operating means 15 through the medium of the slide and block

respectively effecting the display of a selected signal.

5. In an automobile, the combination with normally concealed movable signs, or operating means for moving individually either of said signs at will into a display position, the means for operating said signs, said means including two members arranged for movements in a vertical plane and at right angles with each other for the respective signs, and a lever 20 engageable with either of said members selectively to effect movement of the associated signs into their display positions.

Signed at Seattle, Washington, this 16th 30 day of April 1927.

CARL O. LARSON.
